UNITED STATES PATENT OFFICE.

JOSEPH RAUCHBACH, OF NEWARK, NEW JERSEY, ASSIGNOR TO RAUCHBACH-GOLDSMITH CO., A CORPORATION OF NEW JERSEY.

WARDROBE-TRUNK.

1,215,991.

Specification of Letters Patent. Patented Feb. 13, 1917.

Application filed June 21, 1916. Serial No. 104,869.

To all whom it may concern:

Be it known that I, JOSEPH RAUCHBACH, a citizen of the United States, residing at Newark, in the county of Essex and State

5 of New Jersey, have invented certain new and useful Improvements in Wardrobe-Trunks; and I do hereby declare the following to be a full, clear, and exact description of the invention, such as will enable others skilled in the art to which it appertains to

13 make and use the same, reference being had to the accompanying drawings, all to characters of reference marked thereon, which form a part of this specification.

15 This invention relates, generally, to improvements in trunks; and, the present invention has reference, more particularly, to that class of trunks known to the trade as wardrobe trunks provided with a hanging 20 compartment and a garment hanger therein which is pivotally connected with the body of the trunk and is adapted to be swung into an outward relation to the said body when the trunk is opened, so as to permit of easy 25 access and removal of a garment, the hanger being further adapted to be swung back into the interior of the trunk-body and there securely locked in its closed relation.

30 The invention, therefore, has for its principal object to provide in combination with the body of a trunk having a hanging compartment, a hanger pivotally mounted in a hinge-like manner in said hanging compartment which can be manipulated in the manner stated, and is provided with a spring-latch for easily snapping the hanger into its locked relation with the body of the trunk against accidental movement or displacement.

35 40 The invention has for its further object to provide a garment hanger of the character specified for wardrobe trunks, the hanger comprising a main bracket bar hinged to the said trunk-body and provided with the 45 spring-latch, the said bracket-bar being also provided with transversely extending hanger-supports upon which are adapted to be removably mounted individual hangers, the said hanger-supports extending from the 50 said bracket-bar at acute angles thereto, for the purposes hereinafter more fully stated.

55 The invention has for its further object to provide in connection with the trunk-body and the herein specified garment hanger, means connected with the said trunk-body

with which one or more of the said hanger-supports can be brought into supported relation, so as to prevent sagging and inoperative distortion of the garment-hanger when carrying a great many garments.

Other objects of this invention not at this time more particularly enumerated will be clearly understood from the following detailed description of the present invention.

With the various objects of the present invention in view, the said invention consists, primarily, in a wardrobe trunk combined with a garment-hanger of the character hereinafter more fully set forth; and, the invention consists, furthermore, in the several novel arrangements and combinations of the various devices and parts, as well as in the details of the construction of the said parts, all of which will be more fully described in the following specification and then finally embodied in the clauses of the claim which are appended to the said specification and which form an essential part of the same.

The invention is clearly illustrated in the accompanying drawings, in which:—

Figure 1 is a front elevation of a fragmentary portion of the body of a trunk, and the lid hinged thereto, the said parts of the trunk being represented in their opened relation, showing the hanging compartment of the said body, the said view also illustrating, in elevation within the said compartment, a garment-hanger made according to and embodying the principles of the present invention.

Fig. 2 is a horizontal sectional representation of the trunk-body, the said section being taken on line 2—2 in said Fig. 1, with a top or plan view of the garment-hanger.

Fig. 3 is a detail vertical section taken on line 3—3 in said Fig. 2, said section being made on an enlarged scale; and Fig. 4 is a detail horizontal section taken on line 4—4 in Fig. 1, said view also being made on an enlarged scale.

Fig. 5 is a vertical sectional representation of a corner-portion of the trunk-body, showing in connection therewith on an enlarged scale, and in elevation, the pivot-device for hinging the bracket-bar in its position within the hanging compartment of the trunk-body.

Fig. 6 is an end view of the said bracket-bar and the snap-catch secured upon said

bar, said view showing also in elevation a fragmentary portion of that end of one of the transversely extending hanger-supports secured to the said bracket-bar; and Fig. 7 is a face view of a latch-plate secured upon the inner wall of one of the sides of the trunk-body, said Figs. 6 and 7 also being drawn upon enlarged scales.

Similar characters of reference are employed in all of the said above described views, to indicate corresponding parts.

Referring now to the said drawings, the reference-character 1 indicates the bottom, 2 and 3 the longitudinally extending sides, 15 and 4 one of the ends of any usual style of trunk-body, the interior of the said body forming what may be termed the hanging compartment 5. Hinged to one of the sides, as 2, by means of hinges 6 of any suitable construction is a suitable trunk-lid, as 7. 20 The said trunk-body, as well as the lid, may be provided with suitable reinforcing corner-pieces or clamps 8, and with suitable catches, as 9, or other suitable locking or fastening devices.

25 Suitably secured in one of the corner-portions formed by the side 3 and the end 4 of the trunk-body, and at or near the open part of the said body, by means of rivets 10, or other suitable fastening devices, is an angle-iron or bracket-like element comprising two angularly disposed members 11 and 12, the member 12 being formed with a suitably disposed hole or opening, as 13, for the reception of the one end-portion of a pintle or pivot-pin 14. Suitably secured upon the lower portion of the said member 11, by means of rivets 15 or other suitable fastening devices, is a plate 16 which is formed at its upper end-portion with a right-angled member 17, curved as at 18, and then bent backwardly as at 19, in a direction over the said member 17, so as to provide a suitable spring-support, substantially as illustrated in Figs. 1 and 5 of the drawings. The 40 spring-support is also provided with a suitably disposed hole or perforation, as 20, in alignment with the hole or opening 13, for the reception in said hole or opening 20 of the other end-portion of the above-mentioned pintle or pivot-pin 14.

Oscillatorily mounted upon that portion of the pintle or pivot-pin 14, located between the two members 12 and 19, is the 45 tubular pintle-receiving portion 21 of a hinge-plate consisting of the two plate-like members 22 and 23 which are suitably secured together, preferably by means of rivets 24, or other suitable fastening devices.

50 The said plate-like member 22 is also formed with an outwardly bent or pressed portion, as 25, providing with a portion of the plate-like member 23 a receiving pocket in which is arranged the one end-portion 27 55 of a suitable bracket-bar, as 26, the said

parts being secured in their assembled relation by a rivet 28, or other suitable fastening means.

The said bar 26 is of the proper length so that when in its closed relation within the 70 upper portion of the hanging compartment it will extend laterally across the opening of the trunk-body, and the end-portion 29 of the said bar 26 will terminate at a point close to the inner surface of the side 2 of the 75 trunk-body, as clearly illustrated in Figs. 1, 2 and 4 of the drawings.

Suitably secured by means of rivets or other suitable fastening means upon the inner face of the said side 2, directly back of the said end-portion 29 of the bar 26, and in proper alignment with the pintle or pivot-support upon the other side 3 of the trunk-body, is a latch-engaging element consisting, essentially, of a main plate-like body 31 secured by means of the said rivets 30 to the said side 2. The said plate 31 is formed at the proper position with a part 32 extending inwardly at an acute angle to the face of said plate, said plate being cut away, as 90 at 33, so as to leave a latch-engaging edge 34. Extending inwardly at either end of the said latch-engaging edge 34, are a pair of members, as 35 of any suitable marginal configuration, each member 35 being provided with a post or finger 36, extending laterally toward the side 2 of the trunk-body. The free ends of the said posts or fingers abut upon the inner face of the side 2, as shown in said Fig. 4, said posts or fingers serving as a suitable stiffening or reinforcing means, as will be clearly evident. 95 100

Suitably secured upon the inner surface of the said end-portion 29 of the bracket-bar 26, by means of rivets 37, or other suitable fastening means, is a latch-receiving element which consists, essentially, of a pair of parallel members 38 connected, as at 39, each member 38 being angularly bent so as to provide portions 40 which form a spring-receiving chamber 41. Each portion 40 has a laterally extending base-member 42, each member 42 being perforated for the reception of the rivets 37 for the purpose of securing the latch-receiving element upon the 110 front face of the end-portion 29 of the bracket-bar 26, substantially as shown in Figs. 2 and 4 of the drawings. 115

Pivotedly mounted between the said parallel members 38 upon a pin 43 is a latch-member 44 having a nosing, as 45, adapted to be forced into holding engagement with the latch-engaging edge 34 when the said nosing enters the space 33 between the members 35 in the manner shown in Fig. 4 of 125 the drawings.

The said latch-member 44 is also provided with a suitable projection, as 46, adapted to be brought into stopped or arrested engagement with the edge 47 of the connecting 130

member 39, as shown in said Fig. 4 and the purpose of which is self-evident. An arm 48 is also provided in connection with said latch-member 44, said arm being formed 5 with a fingerpiece, as 49, extending into and through, and being movably disposed in an opening 50 of any suitable conformation, with which the said bracket-bar 26 is provided. Within the previously-mentioned 10 spring-chamber 40 is a suitable spring, which under normal initial conditions, when the garment-hanger is closed into the hanging compartment of the trunk, maintains the latch-member 44 in its locked or retained 15 engagement with the latch-engaging edge 34, as will be clearly understood. One preferred form of spring for accomplishing the purpose of the present invention consists, essentially, of a member 51 lying in 20 contact with the inner surface of the end-portion 29 of the bracket-bar 26, said member 51 having a heel or stud, as 52, extending into a hole or perforation 53 in said end-portion 29 so as to hold the spring in place. 25 Connected with said member 51, as at 54, is another spring-member or arm 55 in forcible engagement with the lower edge-portion 156 of the latch-member 44.

Upon its inner face the said bracket-bar 26 has also secured thereon, by means of rivets 56, or other suitable fastening means, rearwardly extending arms or hanger-supports, as 57, for the suspension thereon of a suitable number of removable garment 35 hangers 58 of any desirable and well-known construction. Each hanger-support or arm 57 is preferably made of metal and is desirably of U-shape cross-section so as to give proper strength, the said arms being provided 40 at one end with perforated ears 59 for the reception of the rivets 56 by means of which the said arms 57 are secured to the bracket-arm 26.

One or both of the said arms 57 are provided 45 at their opposite free ends with angularly bent members, as 60, formed with the holes or perforations 61, providing suitable eyes, adapted to be brought into supporting registration with the extensions 63 extending 50 inwardly from the inner surface of the end 4 of the trunk-body and connected with the stud-like elements 62 suitably secured in the manner illustrated in Figs. 2 and 3 of the drawings.

55 While this arrangement of one or more of said supporting studs is not essential for the purposes of the present invention, still such arrangement of stud or studs may be desirable, since thereby any sagging or distortion of the garment-hanger, when weighted down with a large number of garments or with heavy garments is clearly obviated.

Another desirable feature of the present invention is to arrange the said rearwardly 60 extending hanger-supports or arms 57 at

acute angles to the inner surface of the bracket-bar 26, substantially as illustrated in Fig. 2 of the drawings, so as to permit the complete garment-hanger to swing past the latch-receiving member, when moving the device from its position within the hanging-compartment 5 outwardly therefrom into the position indicated in the dotted outline in said Fig. 2, or when returning the garment-hanger from said dotted position back 75 into the interior of the trunk-body.

The operation of the device will be clearly understood from the foregoing description and from an inspection of the several figures of the drawings and need not therefore be more fully described.

The nosing 45 of the latch-member 44 is readily released by the operator from its holding or retaining engagement with the edge 34 of the latch-receiving device when the finger-piece 49 is moved in the direction of the arrow α in Fig. 4 of the drawings, thereby permitting the hanger to be swung outwardly from the trunk-body into the position indicated in the dotted outline in said Fig. 2 for the removal of any one or more of the individual garment-hangers 58. When the main garment hanger is again turned into its closed relation within the trunk-body, the nosing 45, at the proper time, rides 95 readily over the inclined member 32 and automatically snaps into its holding engagement with the retaining edge 34, whereby the latch-device is held by the action of the spring within the chamber 40, so that the 100 garment-hanger will be positively held against movement or banging about within the closed trunk during transit of the latter.

I am fully aware that some changes may be made in the general arrangements and 105 combinations of the several devices and parts, as well as in the details of the construction of the said parts, without departing from the scope of the present invention as set forth in the foregoing specification, 110 and as defined in the clauses of the claim which are appended thereto. Hence, I do not limit my invention to the exact arrangements and combinations of the various devices and parts as described in the said 115 specification, nor do I confine myself to the exact details of the construction of the said parts as illustrated in the accompanying drawings.

While in the foregoing I have described 120 the complete hanger as pivotally disposed within the trunk-body, it will be evident that the device may just as readily be disposed within the chambered portion of the trunk-lid or cover.

I claim:

1. The combination with a chambered member of a trunk, of a hanger pivotally mounted within said member, said hanger comprising a bracket-bar, supporting arms 130

extending rearwardly from said bar, and means connected with said chambered member with which a supporting arm can be brought into supporting relation to prevent sagging.

2. The combination with a chambered member of a trunk, of a hanger pivotally mounted within said member, said hanger comprising a bracket-bar, supporting arms 10 extending rearwardly from said bar, an eye-member at the free end of one of said supporting arms, and a supporting stud connected with said chambered member with which said eye-member can be brought into supporting registration to prevent sagging.

3. The combination with a chambered member of a trunk, of a hanger pivotally mounted within said member, said hanger comprising a bracket-bar, supporting arms 20 extending rearwardly from said bar, and means connected with said chambered member with which a supporting arm can be brought into supporting relation to prevent sagging, a latch-retaining member connected with said chambered member, and a spring-latch pivotally mounted with relation to said bracket-bar adapted to be sprung into holding engagement with said latch-retaining member, said spring-latch being provided 25 with a fingerpiece for releasing the same from said latch-retaining member.

4. The combination with a chambered member of a trunk, of a hanger pivotally mounted within said member, said hanger comprising a bracket-bar, supporting arms 35 extending rearwardly from said bar, an eye-member at the free end of one of said supporting arms, and a supporting stud connected with said chambered member with which said eye-member can be brought into supporting registration to prevent sagging, a latch-retaining member connected with said chambered member, and a spring-latch pivotally mounted with relation to said bracket-bar adapted to be sprung into holding engagement with said latch-retaining member, said spring-latch being provided 40 with a fingerpiece for releasing the same from said latch-retaining member.

5. The combination with a chambered member of a trunk, of a hanger pivotally mounted within said trunk, said hanger comprising a bracket-bar, and a supporting arm extending rearward at an acute angle 55 from said bar.

6. The combination with a chambered member of a trunk, of a hanger pivotally mounted within said trunk, said hanger comprising a bracket-bar, supporting arms 60 extending rearwardly and at acute angles from said bar, and means connected with said chambered member with which a supporting arm can be brought into supporting relation to prevent sagging.

7. The combination with a chambered

member of a trunk, of a hanger pivotally mounted within said trunk, said hanger comprising a bracket-bar, supporting arms 70 extending rearwardly and at acute angles from said bar, an eye-member at the free end of one of said supporting arms, and a supporting stud connected with said chambered member with which said eye-member can be brought into supporting registration to prevent sagging.

8. The combination with a chambered member of a trunk, of a hanger pivotally mounted within said trunk, said hanger comprising a bracket-bar, supporting arms 75 extending rearwardly and at acute angles from said bar, and means connected with said chambered member with which a supporting arm can be brought into supporting relation to prevent sagging, a latch-retaining member connected with said chambered member, and a spring-latch pivotally mounted with relation to said bracket-bar adapted to be sprung into holding engagement with said latch-retaining member, said spring-latch being provided with a fingerpiece for 80 releasing the same from said latch-retaining member.

9. The combination with a chambered member of a trunk, of a hanger pivotally mounted within said trunk, said hanger comprising a bracket-bar, supporting arms 85 extending rearwardly and at acute angles from said bar, an eye-member at the free end of one of said supporting arms, and a supporting stud connected with said chambered member with which said eye-member can be brought into supporting registration to prevent sagging, a latch-retaining member connected with said chambered member, and a spring-latch pivotally mounted with 90 relation to said bracket-bar adapted to be sprung into holding engagement with said latch-retaining member, said spring-latch being provided with a fingerpiece for releasing the same from said latch-retaining member.

10. The combination with a chambered member of a trunk, of a bracket-bar pivotally mounted at one end within said chambered member, said bracket-bar being pro-

vided at its other end with an opening, a latch-retaining member connected with said chambered member comprising a plate secured to a wall-portion of said chambered member, and an inclined portion extending 115 from said plate, said inclined portion having a latch-engaging edge, a latch-receiving element mounted upon said bracket-bar, consisting of a pair of parallel members and a connecting member; and a spring-actuated latch-member pivotally mounted between said parallel members, said latch-member having a nosing adapted to be brought into retaining engagement with said latch-engaging edge, a stop-projection adapted to be 120

125

130

brought into engagement with the connecting member of said latch-receiving element, an arm extending from said latch-member, and a fingerpiece connected with said arm, said fingerpiece extending into and through the opening in said bracket-bar, and being movably disposed in said opening, and a reinforcing post extending rearwardly from the said latch-retaining member.

11. The combination with a chambered member of a trunk, of an angle-iron mounted in said chambered member, a pintle-support consisting of a plate secured to one of the arms of said angle-iron, a right-angled member connected with said plate and a spring-like supporting member connected with said right-angled member, said spring-like supporting member extending above and over said right-angled member, a hinge-pin mounted between the other arm of said angle-iron and the said spring-like supporting member, a hinge-device mounted upon said pin, a bracket-bar secured to said hinge-device, said bracket-bar being provided at its other end with an opening, a latch-retaining member connected with said chambered member comprising a plate secured to a wall-portion of said chambered member, an inclined portion extending from said plate, said inclined portion having a latch-engaging edge, a latch-receiving element mounted upon said bracket-bar, consisting of a pair of parallel members and a connecting member, and a spring-actuated latch-member pivotally mounted between said parallel members, said latch-member having a nosing adapted to be brought into retaining engagement with said latch-engaging edge, a stop-projection adapted to be brought into engagement with the connecting member of said latch-receiving element, an arm extending from said latch-member, and a fingerpiece connected with said arm, said fingerpiece extending into and through the opening in said bracket-bar, and being movably disposed in said opening.
12. The combination with a chambered

member of a trunk, of an angle-iron mounted in said chambered member, a pintle-support consisting of a plate secured to one of the arms of said angle-iron, a right-angled member connected with said plate and a spring-like supporting member connected with said right-angled member, said spring-like supporting member extending above and over said right-angled member, a hinge-pin mounted between the other arm of said angle-iron and the said spring-like supporting member, a hinge-device mounted upon said pin, a bracket-bar secured to said hinge-device, said bracket-bar being provided at its other end with an opening, a latch-retaining member connected with said chambered member comprising a plate secured to a wall-portion of said chambered member, an inclined portion extending from said plate, said inclined portion having a latch-engaging edge, a latch-receiving element mounted upon said bracket-bar, consisting of a pair of parallel members and a connecting member, and a spring-actuated latch-member pivotally mounted between said parallel members, said latch-member having a nosing adapted to be brought into retaining engagement with said latch-engaging edge, a stop-projection adapted to be brought into engagement with the connecting member of said latch-receiving element, an arm extending from said latch-member, and a fingerpiece connected with said arm, said fingerpiece extending into and through the opening in said bracket-bar, and being movably disposed in said opening, and a reinforcing post extending rearwardly from the said latch-retaining member.

In testimony, that I claim the invention set forth above I have hereunto set my hand this 16th day of June, 1916.

JOSEPH RAUCHBACH.
